[57] **CLAIM**

The ornamental design for a connecting arm for the automotive navigation system, as shown.

DESCRIPTION

FIG. 1 is a rear, top and right side perspective view of a connecting arm for the automotive navigation system, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line showing is for illustrative purposes only and forms no part of the claimed design.
